JAMES C. ARMS, OF NORTHAMPTON, MASSACHUSETTS.

Letters Patent No. 78,914, dated June 16, 1868.

IMPROVEMENT IN FASTENINGS FOR POCKET-BOOKS, &c.

The Schedule referred to in these Letters Patent and making part of the same.

TO ALL WHOM IT MAY CONCERN:

Be it known that I, JAMES C. ARMS, of Northampton, in the county of Hampshire, and State of Massachusetts, have invented certain new and useful Improvements in Clasps for Pocket-Books, &c.; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention consists in a novel construction of a clasp, for use on pocket-books, belts, suspenders, and all similar articles, as hereinafter more fully explained.

Figure 1 represents a pocket-book, in perspective, with my improved clasp applied thereto.

Figure 2 is a plan view of the blanks, of which the clasp is made, before being formed up.

Figures 3, 4, and 5 are sectional views, taken on the line *x x* of fig. 1, and

Figure 6 is a sectional view, taken on the line *z z*.

To construct my improved clasp, I first strike or cut out of sheet metal a rectangular piece, B, with a small strip, *o*, projecting centrally from each end, as shown in fig. 2. Upon the face of this blank, near one end, I then raise an inclined projection, *e*, which may be done by striking it up with a die from the under side, as represented more clearly in fig. 3, or by soldering a piece on its face, as in fig. 5, the object in both cases being to make a raised surface near one end, upon which the strap is to be clasped and held by a slide, *c*, as hereafter explained.

To form this slide, I strike or cut out a small strip of sheet metal, as represented by *c*, fig. 2, of such a length as to reach across the face of the piece B, and have its ends bent around, so as to clasp or engage against the under side of B, as shown more clearly in fig. 6, the dotted lines on *c*, fig. 2, showing where the bends are formed in the strip to give it the required form. This slide is to be so formed that when it is slipped on to the piece B, there will be a small space left between the inner faces of the two, of sufficient size to permit the strap to be inserted between them, when the slide is shoved down to the thin or flat end of B.

The piece B is bent transversely, at a right angle, at the points indicated by the dotted lines on B, fig. 2, so that when the piece is attached to the pocket-book or other article, by inserting the tangs *o* through holes, and bending them down on the inside, as shown in fig. 4, there shall be space enough left between the under side of B and the face of the article to which it is attached, to permit the slide *c* to move freely thereon, as represented in figs. 3, 4, and 5. Instead of constructing the piece B with the raised or inclined face *e*, the same object may be accomplished by forming the blank, B, with inclined sides, as represented by the red lines in fig. 2, and then bending these inclined edges down at a right angle, thus forming an inclined lip, *l*, as shown in fig. 4; and this form is preferred where it is desired to make a large clasp, as these lips render the piece B, more rigid and unyielding.

The face *e*, whether plain or raised, may be roughened by grooves or checks, to hold the strap more firmly, if desired.

The device being thus constructed and applied, is used as follows: The slide *c*, being slipped down to the lower or thin end of piece B, the strap *a* is inserted under the slide, and the slide is then shoved up until it wedges the strap fast between it and the face *e*, thus holding it firmly in position, as represented in figs. 3, 4, and 5. To release the strap, it is only necessary to shove the slide down, when the strap can be at once withdrawn. This clasp is applicable to belts, suspenders, and all similar articles, as well as to pocket-books.

Having thus described my invention, what I claim, is—

The clasp, consisting of the stationary piece B and the slide *c*, when said parts are constructed and united, substantially as shown and described.

JAMES C. ARMS.
